CARBURETOR

Walter Markwart, Chemnitz/Niederwiesa, Germany, assignor to Marklin Apparatebau Gesellschaft mit beschränkter Haftung, Chemnitz, Germany, a corporation of Germany

Application February 9, 1933, Serial No. 656,011
In Germany May 25, 1932

6 Claims. (Cl. 261—62)

The invention relates to a jet carburetor in which a preliminary mixture is fed by way of an atomizing chamber to the induction channel and an over-rich mixture is formed in the atomizing chamber by means of an air nozzle pipe connected with the outer air.

It is already known to provide an extension of the atomizing chamber extending below the level of the fuel, by which it becomes possible for the fuel which is not atomized in the atomizing chamber to be returned by outlets for atomization. The invention consists in a particularly advantageous construction of the carburetor in which the air nozzle pipe is disposed concentrically around the jet tube and is surrounded by a further concentric casing which is connected at the bottom (for instance by holes) with the extension of the atomizing chamber.

If the carburetor operates with an auxiliary air admission for checking the negative pressure at the nozzle of the jet tube, the means necessary for this purpose may likewise be disposed concentrically to the jet tube and be fitted in the space between the jet tube and the air nozzle pipe. As all the casings disposed around the jet tube are in the form of concentric tubular members, their lower flanges can be placed one over the other stepwise and be pressed by a plug introduced into the opening of the atomizing chamber from below against an abutment of the atomizing chamber. In this manner not only is a simple construction of the entire carburetor obtained, but it is also rendered possible for the important component parts of the apparatus to be dismounted and inspected at any time.

The attached drawings show two typical embodiments of the subject of the invention in longitudinal section.

Fig. 1 shows a carburetor according to the invention without provision for the supply of checking air.

Fig. 2 shows a form of construction with provision for the supply of checking air.

In the carburetor according to Fig. 1, the delivery pipe *o* forming the end of the atomizing chamber *i* projects into the induction channel *m*. This delivery pipe on the side remote from the entering current of suction air is provided with the openings *p*. The delivery pipe is enclosed by the throttle valve *q* which, by means of the rod *r*, can be adjusted according to the desired conditions of operation.

The actual atomizing chamber *i* extends into the attachment *s* of the induction channel casing *m*. This attachment is bored out cylindrically and provided at the bottom with a screw-thread *t*. Into this thread is screwed the actual air nozzle pipe *f*. Into a bore of the air nozzle pipe *f* there is introduced the jet tube *a* in such a manner that between the casing of the jet tube

and the casing *f* of the air nozzle pipe there remains a free annular space to which air can be fed by the ducts *g* which communicate with the atmosphere.

Over the air nozzle pipe *f* is placed the cylindrical casing *h* provided at the bottom with openings *k* through which the unatomized fuel which collects in the bottom of the atomizing chamber *i* can return into the annular space between the casings *h* and *f*. The casing *h*, at the top, i. e. at the position *h*¹, is of conical shape. It may be covered in the middle by an atomizing cone *v* in such a manner that the air and the fuel are forced to leave the casing *h* by lateral openings *w*.

At the bottom of the jet tube *a* there is provided a calibrated plug *n*. This nozzle opens into the space *x* at the bottom end of the air nozzle pipe bore which latter is closed by a plug *y*. This space *x* is connected with the passage *z* by the arm *z'* leading to the float chamber.

The described arrangement operates as follows:

In consequence of the current of air acting in the induction channel *m*, fuel mixture is sucked from the atomizing chamber *i* through the holes *p* of the delivery pipe *o*. The fuel mixture is formed by the fuel flowing from the space *x* through the calibrated plug *n* and the jet tube *a* and which is mixed at the exit of the jet tube with the outer air flowing from the annular space *u* of the air nozzle pipe *f*. This preliminary mixing is assisted by the deflection which occurs at the upper end of the casing *h* and particularly by the striking against the atomizing cone *v*.

Any unatomized particles of fuel carried along with the fuel mixture, run along the outer surface of the casing *h* and arrive in the chamber extension between the casing *h* and the cylindrical attachment *s*. The upwardly flowing air in the annular space *u* passes over the upper outlet of the annular ducts *k* between the casings *h* and *f* and by the negative pressure produced draws the returned unatomized fuel through the holes *k* from the chamber extension between the casing *h* and the cylindrical attachment *s* and mixes it with the fuel coming from the calibrated plug *n*.

From Fig. 1 it can be seen that the casing *h* rests on a shoulder of the air nozzle pipe and together with the air nozzle pipe and the jet tube *a* is screwed into the boring of the air nozzle pipe *f* and can be screwed out from below. Thus all the most important parts of the carburetor are united to one member which can easily be dismounted and examined.

In the carburetor operated with checking air according to Fig. 2, *a* is the jet tube and *f* the air nozzle pipe over which the casing *h* which is conically shaped at the top is placed. This casing is also provided with the openings *k* at the bottom, through which the non-atomized fuel

from the extension of the atomizing chamber *i* can flow back for atomization.

Between the jet tube *a* and the air nozzle pipe *f* there is arranged a concentric sleeve *b*. The annular space left between the sleeve *b* and the jet tube *a* is connected at its upper end with the outer air and throughout its length, by the openings *c*, with the interior of the jet tube *a*. The checking air is supplied to the annular space between the jet tube *a* and the sleeve *b*, by an annular duct *e*, which duct is closed to the air nozzle pipe *f* by a casing *d*. The carbureting air is admitted through the port *g*. The jet tube *a* is a separate element from the casing *d* and can be removed by unscrewing from the base *l*.

The fuel in the jet tube *a* and also in the annular space between the jet tube *a* and the sleeve *b* is at the same level as that of the fuel in the float chamber *S* as indicated in the drawings by the chain line. When negative pressure prevails in the atomizing chamber *i* after the throttle valve *q* has been opened or the engine has been started, the fuel is drawn from the jet tube *a*. The fuel which has accumulated in the annular space between the jet tube *a* and the sleeve *b* is sucked through the holes *c*. As soon as the level of the fuel in the annular space sinks, air is drawn in from the outside through the annular space between the sleeve *b* and casing *d* or the channel *e*. This air passes through the holes *c* into the jet tube *a* whereby a pre-mixing and preliminary atomization of the fuel takes place and to a certain extent a fuel foam is formed.

The function of the checking air can be seen from the following:—

The negative pressure in the jet tube *a* sucks the fuel through the calibrated plug *n*. The air of atmospheric pressure which enters through the holes *c* weakens the negative pressure at the nozzle and thereby reduces the quantity of fuel supplied by it. The result is that when the throttle valve *q* is opened and when the fuel located in the jet tube *a* and the surrounding annular space is sucked up, the holes *c* are gradually freed and when the throttle is opened the amount supplied by the main nozzle is checked. With progressive opening of the throttle valve without the checking air the mixture would become too rich, which assumption is based on the laws governing the outflow of liquids.

If the throttle valve is more or less closed, the fuel rises in the annular space between the jet tube *a* and the casing *b*, and collects here for the subsequent opening of the throttle. The already preliminarily atomized fuel issuing from the jet tube *a* is further mixed with the air flowing from the air nozzle pipe *f* and passes by way of the choked opening of the casing *h* into the atomizing chamber *i* and through the holes *p* into the induction channel *m*. The delivery pipe *o* which projects into the induction chamber *m* preferably opens to the atomizing chamber in such a manner that the internal diameter of the delivery pipe is greater than the diameter of the opening at the upper conically shaped end of the casing *h* surrounding the jet tube and the air nozzle pipe. If the sum of all the openings *p* in the delivery pipe *o* is sufficiently great, the preliminary mixture of fuel and air which is accumulated in the atomizing chamber *i* can arrive in the induction channel *m* without throttling.

I claim:—

1. In a carburetor the combination of an induction channel, a mixture delivery pipe provided with holes opening into the induction channel, an atomizing chamber in connection with the open end of the delivery pipe, a float chamber communicating with the atomizing chamber through a calibrated orifice, an atomizing jet tube adapted to receive fuel from the float chamber through said calibrated orifice and discharging the fuel in said atomizing chamber, an air nozzle pipe disposed concentrically around the jet tube, and a concentric casing surrounding the air nozzle pipe and having openings at its lower end connecting the bottom of the atomizing chamber with the annular space between the casing and the air nozzle pipe, said casing terminating at its upper end in a conical member.

2. A carburetor as claimed in claim 1, in which the orifices of the mixture delivery pipe have such a cross-sectional area that the jet of the fuel and air when issuing from the jet tube and the air nozzle pipe may pass without throttling into the delivery pipe.

3. In a carburetor as claimed in claim 1 the arrangement that the internal diameter of the delivery pipe is greater than that of the opening at the upper conically shaped end of the outer casing surrounding the jet tube and the air nozzle pipe.

4. In a carburetor as claimed in claim 1 the arrangement that the casing disposed around the jet tube is in the form of concentric tubular members, the lower flanges of which rest on one another stepwise and are pressed by a plug sealing the bottom of the atomizing chamber, against an abutment on the atomizing chamber.

5. In a carburetor as claimed in claim 1, means for checking the negative pressure at the end of the jet tube, comprising a concentric sleeve between the jet tube and the air nozzle pipe forming an annular space between said sleeve and the jet tube and which is connected at the upper end with the outer air and over its length by openings with the interior of the jet tube, and in which the casing and the sleeve disposed around the jet tube are in the form of concentric tubular members, the lower flanges of which rest on one another step-wise and are pressed by a closure sealing the bottom of the atomizing chamber against an abutment on said chamber.

6. In a carburetor the combination of an induction channel, a mixture delivery pipe provided with holes opening into the induction channel and having an atomizing chamber therein, a float chamber communicating with the atomizing chamber through a calibrated orifice, an atomizing jet tube adapted to receive fuel from the float chamber through said calibrated orifice and discharging the fuel in said atomizing chamber, an air nozzle pipe disposed concentrically around the jet tube, and a concentric casing surrounding the air nozzle pipe and having openings at its lower end connecting the bottom of the atomizing chamber with the annular space between the casing and the air nozzle pipe, said casing terminating at its upper end in an apertured conical member extending over the end of the jet tube.

WALTER MARKWART. 70
